UNITED STATES PATENT OFFICE.

JOSEPH L. WRIGHT, OF WASHINGTON, DISTRICT OF COLUMBIA, ASSIGNOR, BY MESNE
ASSIGNMENTS, TO FREDERICK C. STEVENS, OF ATTICA, NEW YORK.

TELEPHONE-EXCHANGE SYSTEM.

1,137,372.

Specification of Letters Patent. Patented Apr. 27, 1915.

Application filed March 23, 1912. Serial No. 685,896.

To all whom it may concern:

Be it known that I, JOSEPH L. WRIGHT, a citizen of the United States, and resident of Washington, District of Columbia, have invented certain new and useful Improvements in Telephone-Exchange Systems, of which the following is a specification.

My invention relates to telephone exchange systems, and especially to that class wherein automatic switching mechanism is employed in establishing connections between subscribers.

The object of my invention is to provide improved means for controlling the automatic switching mechanism.

It is customary in systems wherein switching mechanism is employed, to provide suitable impulse devices for driving or controlling the various automatic switches. For instance, in order to connect a switch with a particular group of trunks or lines, impulses are transmitted in a predetermined order, and the switches respond to these impulses and are driven to the proper trunks or lines. In systems operated in this manner, it is necessary to have the sending devices, relays, and magnets adjusted or timed, so that they will coöperate so as to effect proper connections.

The object of my invention is to do away with, or avoid all marginal features or fine adjustments between the relays and magnets of the various switches. Instead of providing sending devices for driving the switches to the proper trunks or lines, I simply use a device for controlling the action of the switches, wherein the necessity for transmitting impulses is dispensed with. The switches, when started automatically operate until the wipers reach the contact corresponding to the position of the sending device.

In the present instance, I have shown my invention as applied to a semi-automatic system, wherein the switches for effecting connections between subscribers are controlled by operators. The controlling device, as shown, consists of several rows of buttons, arranged similar to those of an adding machine. These buttons are arranged so as to connect certain circuit combinations to the controlling wire or wires which are connected to the automatic switches in a certain order. These control

wires are connected in sequence to the wipers of the various automatic switches. These wipers in turn pass over contacts in banks of the automatic switches. The contacts of these banks are connected in reverse order to those of the buttons of the controlling device. If number 1 button of the controlling device is set, and the automatic switch is stepping, a circuit will be closed over either one or both of the control wires, when number 1 contact in the banks is reached. If number 10 button is set, a circuit will not be completed over either of the control wires until the tenth contact in the bank is found. By so arranging the contacts of the controlling device and the contacts of the banks, I am able to pick out any particular contact. Instead of having a sending device for driving the switches, I really have what may be termed a stopping device, for as soon as the wipers of the switches reach the proper contact, a circuit is closed through the control wires and the control device, whereby the switch is automatically brought to rest with its wipers resting on the proper contact.

With the foregoing arrangement, each switch magnet can have its own individual or natural time element, as it simply controls its own circuit and steps the switch until the proper contacts are found.

Another feature of this invention is the extreme rapidity in which connections are effected, as there is no time lost as would be the case were a sending device used. Where sending devices are used, it requires just about as much time to call subscriber 1111 as it would to call a subscriber whose number is 9999. With my invention, it would only require one-ninth of the time to call 1111 as to call 9999, as there is absolutely no time lost in effecting connections between the various switches.

It will be noted from the foregoing and from the description to follow that the control device has no moving parts to work in unison with the switching mechanism. The switching mechanism when active is brought to rest at the proper time by means of certain circuit combinations set up between the switching mechanism and the control device. This latter device remains passive at all times regardless of the action of the switching mechanism which it controls.

My invention is illustrated in the accompanying drawings, wherein:

Figure 1 shows a subscriber's line and control circuit. Fig. 2 shows a primary and first selector switch circuit. Fig. 3 shows a second selector switch circuit. Fig. 4 shows a connector circuit. Fig. 5 shows a subscriber's line circuit. Fig. 6 shows a key-set control circuit. Fig. 7 shows the operator's key-set switch circuit. Fig. 8 shows the controlling device. Fig. 9 shows how the combinations between the controlling device and bank contacts are effected.

Referring to Fig. 1 the subscriber station A is equipped with apparatus usually in common battery systems and the line wires from this station terminate at the central office in a line relay 2. The line relays are divided into groups, there being ten groups to each one hundred lines. The windings of each group of ten relays are common to the winding of a group relay 3 so that when any line relay is energized, the group relay associated with it is also energized. The group relay when operated makes the row contact in the primary switch busy, while the line relay when operated makes the individual test contact in the primary switch busy.

The switch W is common to a group of one hundred lines and it is made to rotate whenever a call is originated. In rotating this switch picks out an idle primary switch and starts the same hunting for the calling line.

Referring now to Fig. 2, the primary switch is shown at C. On the spindle of the switch is mounted a row wiper 63 which passes over the row contacts when the switch rotates. This switch first rotates to pick out the group of calling lines and then steps vertically until the calling line is found. The first selector switch is shown at D and is similar to the primary switch. The spindle of this switch carries a set of row wipers which engage row contacts when the switch is rotating and also another set of wipers which engage the vertical rows of contacts after the switch finds the proper row contact. All of the primary, first selector, and connector switches are provided with two distinct kinds of wipers, namely, row wipers to pick out the group while the switch rotates and vertical wipers which pick out contacts in the vertical rows. The primary and key-set switches are only provided with a single row wiper while the selector and connector switches are provided with two row wipers. The row wipers of the selector and connector switches in passing over the contacts cause certain circuit combinations in relation to the operator's key-board or controlling device.

Referring again to Fig. 2, the wipers 63 of the primary switch C and the wipers 56 of the first selector switch D are joined as indicated by the heavy lines for conversa-

tional purposes. The tip and sleeve conductors are separated by the condensers 43 and 44. Relay 23 and the retardation coil 26 transmit talking current to the calling subscriber. Relay 21 is the starting relay of the primary switch and corresponds to the line relay 2, (Fig. 1) as it controls the action of the operator's key-set switch, Fig. 7. Relay 22 is the row test relay while 24 is the individual test relay. Relay 25 is operated when the key-set switch picks out the trunk and remains energized while the various switches are being controlled and until the connection between the calling and the called subscriber is established. Relay 27 is the test relay of the first selector switch and remains energized while the test wipers are passing over busy contacts. Relay 28 is energized whenever either the rotary or vertical magnets of the primary switch are operated and also when the vertical and rotary magnets of the first selector switch are operated. The circuits of these magnets are normally completed through the back contacts of this relay 28, and so therefore whenever it is actuated the magnet circuits are broken. The action thus set up between the relay and the magnets cause the latter to vibrate and continue to do so until their energizing circuits are opened. The controlling relays 81 and 82 are connected to the row wipers as shown, and either one of these relays operating when the proper circuit combination is formed between the key-board and the contacts which these wipers pass over closes the circuit of the shifting relay 29. The action of this latter relay disconnects the rotary magnet of the first selector switch and in its place connects the vertical magnet. As the first vertical step of the first selector switch the controlling relays 81 and 82 are disconnected from the tip and sleeve conductors of the trunk.

Referring now to Fig. 3 the second selector switch at E is similar to that of the first selector switch and is controlled in the same manner. The two control relays are connected to the row wipers and when either one or both are operated the circuit of the rotary magnet is disconnected and the vertical magnet connected in its place.

Referring now to Fig. 4 the connector switch at G is provided with a set of wipers 355 leading to the talking conductors of the called line and a test wiper 360 which is also a part of the circuit of the cut off relay. This switch besides having the row wipers 375 and 380 also has a pair of wipers 365 and 370. These latter wipers are connected to the row wipers and also to the control relays 305 and 310. In the connector switch it is necessary to pick out a predetermined individual contact in the vertical row as well as to pick out a predetermined row contact, thus necessitating the additional wipers 365, 130

and 370. Relay 315 is operated at the first action of either of the two control relays and connects or closes the circuit of the rotary magnet causing the connector switch 5 to rotate. When the control relays operate after the switch has rotated, the circuit of the relay 330 is closed, thereby disconnecting the rotary magnet and in its place connecting the vertical magnet. The switch now 10 steps vertically until the wipers 365 or 370 close the circuit of one or both of the control relays. When such a circuit is closed either one of these relays acting will close the circuit of relay 325, thereby disconnecting the 15 vertical magnet and causing the wipers of the connector switch to rest on the contacts of the called line. This last action of either one of the control relays 305 or 310 connects the test relay 345 to the test wiper 360. If 20 the called line is busy, the action of this relay will close the circuit of the release magnet 385 and restore the switch and also place a suitable busy tone signal to the calling subscriber. If the called line is not busy then 25 the relay 330 will be placed in series with the cut-off relay. The action of relay 330 disconnects the control relays and closes the tip and sleeve conductors of the trunk. Relay 350 is the ringing relay and is operated in- 30 termittently by means of the commutator 500 until the called party answers, whereupon this relay is disconnected. Relay 335 and retardation coil 340 transmit talking current to the called subscriber. When the 35 called subscriber answers he controls the action of the connector switch, while the calling subscriber controls the action of the primary, first and second selector switches.

Referring now to Fig. 5 the subscriber's 40 station and line equipment is the same as that of Fig. 1, the only difference being that the control circuit is not shown in detail.

Referring now to Fig. 6 the switch shown at Y corresponds to the switch W, Fig. 1 45 and picks out an idle key-set switch.

Referring now to Figs. 7 and 8 the key-set switch and operator's key-board is shown. The switch M is similar and acts in the same manner as the primary switch, Fig. 2. The 50 wipers 167 connect to the tip and sleeve side the trunk shown in Fig. 2 over which the operator converses with the calling subscriber and over which the action of the various switches are controlled. 168 is the 55 row wiper and picks out the particular group of trunks in which the calling trunk is located. Relay 154 is the individual test relay and acts when the trunk in the group is found. Relay 156 is the signal relay and 60 pulls up in series with relay 25, Fig. 2. Relay 152 is the starting relay and corresponds to relay 21, Fig. 2, while 153 is the row test relay. Relay 155 is operated when the answering button 248 is depressed and connects 65 the operator's telephone across the tip and

sleeve conductors of the trunk. Relay 157 is operated when the starting button 247 is pressed and connects the control relays in series with the tip and sleeve conductors and the wipers of the shifting switch N. When 70 either one or both of the control relays are operated the magnet of the shifting switch is closed causing the wipers to step on to the next contact. The operator's key-board shown in Fig. 8, consists of four rows of buttons, each row having ten buttons. The corresponding buttons in each row are multiplied and lead to battery, generator, condenser, etc., as shown. The contacts of button number 1 of each row are connected to 80 the generator 230. When number 1 button of any row is pressed, generator current is connected directly across the tip and sleeve control wires. Number 2 button of each row is connected to one side of the generator 230 and when this button of any row is pressed the generator is connected to the sleeve control wire. When number 3 button of any row is pressed, generator 230 is connected to the tip control wire. When number 4 button is pressed battery B-B is connected directly across the tip and sleeve control wires. When button 5 is pressed the battery is connected to the sleeve control wire and when 90 number 6 button is pressed the battery is connected to the tip control wire. When button number 7 is pressed the tip and sleeve control wires are directly short circuited. When button number 8 is pressed the ground is connected to the sleeve control wire and 100 when number 9 button is pressed ground is connected to the tip control wire. When number 10 button is pressed the condenser 231 is connected directly across the tip and 110 sleeve control wires. The control wires from the various strips of buttons are connected in order to the tip and sleeve trunk wires by the action of the shifting switch N. At the first step of the switch the control wires of the first row of buttons are connected to the tip and sleeve conductors each in series with one of the control relays as shown. As soon as these control relays operate, which happens when the proper circuit combination is set up between the key-board and the wipers of the selector or connector switches, the switch N takes a step and disconnects the control wires of the first row of buttons and connects the control wires of the second set of buttons and so on.

The key-board arrangement shown on Fig. 8 will take care of an exchange having ten thousand lines capacity and for larger exchanges it will only be necessary to add the necessary buttons and insert the proper selector switches.

Fig. 9 shows how the various circuit combinations are set up between the key-board and the bank contacts of the switches. The bank contacts are shown at 860 to which bat-

tery, generator and condenser are connected, while a single row of buttons are connected as in Fig. 8. Suppose for instance that number 1 button is pressed and the wipers 850 start to rotate; when the wipers of the switch reach the first contact to which the condenser 831 is connected a circuit will be closed as follows: ground side of generator 230, relay 840, relay 810, top row wiper of 10 the switch, condenser 831, lower row wiper, relay 820, relay 830, contacts of button 1 to the opposite side of generator 230. All of the relays 810, 820, 830 and 840 are operated. The action of relays 810 and 820 close the 15 shifting or control relay of the switch and cut off the rotary magnet. The action of relays 830 and 840 close the circuit of the shifting switch N, disconnecting the first row of buttons and connecting the next row 20 in order. Suppose number 5 button were pressed then the switch wipers 850 would rotate until the fifth set of contacts are reached, whereupon a circuit would be closed as follows: negative side of battery B-B, 25 contacts of button 5, relay 840, relay 810, top row wiper to ground through the row contact. The energizing of relays 810 and 840 shift the control circuits of their respective switches as before. In case number 30 10 button is pressed a circuit will not be closed until the row wipers of the switch reach the last contact, whereupon the following circuit is closed: ground side of generator 230, row contact, lower wiper, relay 35 820, relay 830, contacts of button 10, condenser 231, relay 840, relay 810, upper row wiper, row contact to the opposite side of generator 230. The operation of these relays close their respective control circuits as 40 before. With the arrangement as shown in this figure I am able to cause the various switches to pick out or come to rest on any desired contact without the use of a sending device for driving the switches. It, of 45 course, follows that various other combinations than those actually shown could be made and the number of combinations increased. The switches I have employed simply step around ten contacts and then 50 step vertically to the tenth contact to pick out the highest number, so therefore it is only necessary for me to show circuits for causing ten combinations. In the connector switch individual wipers also pass over rows 55 of contacts arranged like those shown at 860, Fig. 9.

Other features in connection with the various figures will be brought out in the detailed description of operation.

60 The operation of my system is as follows: The subscriber at A upon removing his receiver closes the circuit of the line relay 2 in series with the group relay 3. This latter relay operating closes the circuit 65 of relay 4 which in turn connects ground to

one terminal of the relay 5 and also closes the circuit of the stepping magnet 7. The stepping magnet operating closes the circuit of relay 6 which in turn opens the circuit of the magnet itself causing it to vibrate and 70 step the switch W. This switch will continue to rotate until an idle primary switch such as shown in Fig. 2 is found. As soon as such a switch is found, the relay 5 is placed in series with relay 21, (Fig. 2,) by 75 the following path: ground, contact of relay 4, 5, 18, W, 14, 21, 70, contact of relay 24 to battery B. The relay 5 operating opens the circuit of the magnet 7 bringing the switch W to rest. Relay 21 operating 80 closes the circuit of the rotary stepping magnet 31 by the following path: battery B, 80, back contact of relay 24, 71, contact of relay 28, back contact of relay 22, 31 to ground. The operation of magnet 31 causes 85 the switch C to operate until the wiper 64 reaches the busy row contact. The wiper 64 is carried on the same spindle with the wipers 63 and 65, and while the switch is rotating the wiper 64 passes over contacts 90 leading to the group relay 3. As there are ten of these group relays to each one hundred lines it follows that the wiper 64 in rotating to its extreme position will pass over ten contacts.

95 There are ten sets of individual contacts arranged in vertical rows associated with each row contact and which the wipers 63 and 65 respectively engage. It follows therefore that after the switch picks out the 100 group in which a line is calling, it will afterward step vertically until the wipers engage the contacts of the calling line. As soon as the row contact is found, the circuit of relay 22 is closed as follows: battery B, 105 80, back contact of relay 24, 71, 22, 64, 13, contact of relay 3, to ground. The relay 22 in operating disconnects the rotary magnet 31 and in its place connects the vertical magnet 30, thereby causing the switch to 110 step vertically until the busy individual test contact is found. As soon as such a contact is found the circuit of relay 24 is closed as follows: battery B, 24, 68, contacts of relay 22, 67, 11, contacts of relay 2 to ground through the contacts of relay 1. Relay 24 operating opens the wire 71 and disconnects relay 22 which in falling back disconnects relay 24 from the wire 67 and connects it instead to wire 66, thereby placing relays 115 24 and 1 in series. The operating of relay 1 disconnects the line relay 2 and the group relay 3. Relay 24 connects battery to the windings of relays 23 and 25 and the falling back of relay 22 connects ground to the 120 coil 26, thereby supplying the calling subscriber with talking current.

125 Relay 21 remains energized until the primary switch finds the calling line and until the key-set switch finds the trunk. 130

Relay 21, when first actuated, places battery on the wire 79 to relay 130 and also places battery to wire 62 which is connected to the individual test contact of the key-set switch, (Fig. 7.)

5 Relay 130 closes the circuit of the stepping magnet 133 of the switch Y through the normally closed contacts of relays 131, 132. The magnet in operating closes the 10 circuit of the interrupter relay 134, thereby causing the magnet to vibrate and the switch to rotate until an idle key-set switch is found. When such a switch is found as shown in Fig. 7, relay 131 is placed in series 15 with relay 152 by the following path: ground, contacts of relay 130, 131, 138, Y, 140, 152, 195, 196, 197 to battery B through the operator's jack 400. Relay 131 operating places battery on wire 136 to relay 132. 20 As soon as this latter relay operates, ground is placed on the wire 138, thereby shunting relay 131. This direct ground placed on wire 138 makes the wire 140 which is multipled to other Y switches busy. The operating of relay 132 also places ground on the 25 row wiper of the key-set switch by the following path: ground 139, Y, 141, to the row contact.

The operation of relay 152 connects 30 ground to the rotary magnet 165 through the back contact of relay 153 causing the switch M to rotate. This switch will rotate until the busy row contact is found, whereupon the circuit of relay 153 will be closed 35 as follows: battery B, contacts of relay 152, 176, 153, 171, 168, 141, 139, contacts of relay 132 to ground. The key-set switch M operates in the same manner as the primary switch C, (Fig. 2.) Relay 153 disconnects 40 the rotary magnet 165 and connects in its place the vertical magnet 164, thereby causing the switch to step vertically until the busy individual test contact is found. The finding of this contact closes the circuit of 45 relay 154 as follows: ground, 154, 172, 62, 80, contacts of relay 21 to battery B. Relay 154 disconnects relay 152, thereby cutting off the vertical magnet and causing the key-set switch to rest on contacts leading to the 50 calling primary trunk. Relay 152 becoming disengaged opens the circuit of relay 153 and this latter relay in falling back places relays 156 and 25 in series by the following path: ground, back, contact of relay 153, 175, back 55 contact of relay 157, 202, contact of relay 155, 156, 193, contacts of relay 158, 170, 59, 25 to battery B through the contacts of relay 24. The operating of relay 25 (Fig. 2) disconnects relay 21 and also relay 5, (Fig. 60 1). The releasing of relay 5 frees the switch W allowing it to pick out other primary 65 switches. Relay 156 operating places battery on wires 181 and 183 causing the lamps 243 and 244, (Fig. 8,) to light. As soon as relay 21 in Fig. 2 became disconnected bat-

tery was removed from the individual test contact of the key-set switch, thereby allowing relay 154 to fall back. Relay 21 also releases relay 130, thereby restoring relay 132 so as to allow the switch Y to be used 70 by other trunks in picking out key-set switches.

In the present system I have provided ten primary switches such as shown in Fig. 2 for each one hundred lines. Each group of 75 ten primary switches is in turn provided with one Y switch for picking out idle key-set switches. The percentage and grouping of the trunks and lines can be varied to 80 suit traffic conditions.

The wire 141 leading from the Y switch to the row contacts of the key-set switch is not multipled. The Y switch picks out an idle key-set switch and then places ground on the row contact of the selected switch and 85 these row contacts are not multipled. This arrangement prevents interference between other Y switches and also between the key-set switches. In no case is ground placed on more than one row contact of any key-set 90 switch at the same time.

In Fig. 1 the switch W is individual to one hundred lines and picks out a group of primary switches, and in this case the row contacts of a group of primary switches are 95 multipled.

The lighting of the two lamps 243 and 244 notifies the operator of a call, and she then presses button 248 closing relay 155. The operation of this relay connects her telephone set across the trunk wires, disconnects 100 relay 156, thereby extinguishing lamps 243 and 244. The lamp 245 is lighted when the relay 155 is operated. The disconnecting of relay 156 also opens the circuit of relay 25, 105 (Fig. 2,) which in falling back closes the tip and sleeve conductors of the trunk, allowing the operator to converse with the calling subscriber.

The operator upon receiving the number 110 desired, which we will assume is 1470, sets up this number on her key-board (Fig. 8) in the following manner. She presses number 1 button in the row R, number 4, in the row S, number 7, in the row T, and number 115 0 in the row U. The row R represents the thousands, the row S the hundreds, the row T the tens and the row U the units numerals of the desired line. After setting up these buttons she presses the starting button 247 120 closing the circuit of relay 157 as follows: ground, contacts of button 247, 186, 157, 193, contacts of 158, 170, wiper 169, 59, relay 25 (Fig. 2), contacts of relay 24 to battery B.

The operating of relay 157 disconnects relay 155 and at the same time extinguishes the lamp 245. The energizing of relay 157 places the relay 840 (Fig. 7) and relay 81 (Fig. 2) in series as follows: ground, contacts of 0, contacts of relay 157, 840, 151, 125 180

167, 61, 53, 81, 46, wiper 48 to battery B—B through the contact upon which it normally rests. The energizing of relay 81 closes the circuit of relay 29 as follows: ground, contacts of 81, 42, cam springs 41, 36, 29, 45, contacts of relay 25 to battery B. The energizing of relay 29 closes the circuit of the rotary magnet 34 as follows: battery B, contacts of relay 28, 71, contacts of relay 29, contacts of relay 27, cam springs 40, 34 to ground. The operation of magnet 34 causes the switch D to rotate. The operation of relay 840 (Fig. 7) closes the circuit of the magnet 161 of the distributing switch causing the wipers to take one step. These wipers in stepping, disconnect ground from the relay 840 but connect this relay to wire 221 which is common to certain of the buttons in the first strip. The relay 830 is also connected to the wire 220 which is also common to certain buttons in the first strip.

When the wipers 48 and 49 of the switch D reach the first contacts, a circuit is closed as follows: generator 230, (Fig. 8), contacts of button number 1, 220, N, 830, 150, 60, 82, 47, 49, condenser 831 as shown in (Fig. 9), wiper 48, 46, 81, 53, 61, 167, 151, 840, contacts of relay 157, 0, 221, contacts of button 1 to ground. It will be noted that as soon as the wipers 48 and 49 leave the contacts upon which they normally rest, the relays 81 and 82 and also relays 830 and 840 are de-energized, as the contacts are spaced so that the wipers 48 and 49 always leave one set of contacts before they engage another set. When the relays 81 and 82 are closed the second time by the circuit just traced through the key-board, they close the circuit of relay 27 as follows: ground, through contacts of relays 81 and 82, 42, cam springs 41, 27, 45 to battery B through the contacts of relay 25. The operation of relay 27 disconnects the rotary magnet 34 and in its place connects the vertical magnet 33, and the switch D starts to step vertically to pick out an idle trunk leading to a second selector switch.

The operation of relays 830 and 840 close the circuit of the stepping magnet 161. thereby disconnecting the relays 830 and 840 from the first strip of buttons and connect them instead to the second strip of buttons.

The relay 27 will remain energized until the test wiper 57 finds a contact free from ground, which is the indication of an idle trunk. The relay 27 also has its circuit maintained through the normally closed contacts of relay 28, and to ground through the release magnet 32, as this magnet has ground connected to its winding by the action of the cam springs 41. When the wiper 57 is in the center of a test contact, free from ground, and the relay 28 is energized by the action of the magnet 33, then the test

relay 27 will become de-energized and close the tip and sleeve trunk conductors. While this relay is energized in picking out the idle trunk, the trunk conductors are separated preventing any interference, while passing over busy trunks. At the first vertical step of the switch D, the wipers 48 and 49 are disconnected from the row contacts, thereby preventing any further action of relays 81 and 82.

As soon as an idle second selector is picked out, such as shown in Fig. 3, the circuit of relay 811 is closed as follows: ground, cam springs 41, 75, 32, 72, contacts of relay 28, 58, test wiper 57, 96, 811 to battery B. The energizing of relay 811 closes the circuit of the rotary magnet 87 as follows: battery B, contacts of relay 811, contacts of relay 83, 94, cam springs 106, 99, 87, 100 to ground through the contacts of relay 822. As soon as the row wipers 103 and 104 reach the fourth set of contacts such as shown in Fig. 9, a control circuit is completed as follows: battery B—B, contacts of number 4 button in the row S, 222, N, 830, 150, 60, contacts of relay 27, 54, wiper 56, 90, 84, 97, wiper 103, fourth set of contacts, such as shown in Fig. 9, wiper 104, 98, 85, 91, 56, contacts of relay 27, 53, 61, 167, 151, 840, contacts of relay 157, 0, 223, number 4 button to ground. The operation of relays 84 and 85 close the circuit of the relay 83 by placing ground on the wire 96. The operation of this relay 83 disconnects the rotary magnet 87 and in its place connects the vertical magnet 88 causing the second selector switch E to step vertically and pick out the idle connector switch. At the first step of the switch E, the wipers 103 and 104 leave the row contacts and the relays 84 and 85 are disconnected.

The operation of relays 830 and 840 cause the distributing switch to take another step and disconnect these two relays from the second strip of buttons and connect relay 840 to ground as in the first instance. The test relay 83 will remain energized until an idle connector is found, such as shown in Fig. 4. The action of this relay 83 is controlled in the same manner as relay 27 (Fig. 115 2), and while it is energized it severs the tip and sleeve conductors preventing interference while the switch wipers are passing over busy trunks. As soon as this relay 83 becomes de-energized, the following circuit 120 is established: ground, 0, contacts of relay 157, 840, 151, 167, 61, 53, contacts of relay 27, 56, 91, contacts of relay 83, 101, 302, contacts of relay 330, 324, relay 310, 322, wiper 380 to battery B—B through the contact upon which it normally rests. The operation of relay 310 over this control circuit closes the circuit of the relay 315 as follows: battery B, contacts of relay 310, 309, cam springs 397, 311, 315, 308, 102, 130

93 to ground through contacts of relay 822 (Fig. 3). The operation of relay 315 closes the circuit of rotary magnet 390 as follows: battery B, contacts of relay 325, 333, contacts of relay 315, contacts of relay 320, 318, 390 to ground through contacts of the interrupter relay 385. The action of this magnet causes the switch G to rotate.

The operation of 840 causes the shifting switch (Fig. 7) to take another step, disconnecting ground from the relay 840, and connecting this relay and the relay 830 to the third strip of buttons. When the wipers 375 and 380 of the switch G reach the seventh set of contacts as shown in Fig. 9, a control circuit is established as follows: battery B—B, number 7 contact, wiper 375, 321, 305, 323, contacts of relay 330, 301, 101, contacts of relay 83, 90, 56, 54, contacts of relay 27, 60, 167, 150, 830, N, 224, contacts of button 7 (Fig. 8) 225, 0, contacts of relay 157, 840, 151, 167, 61, 53, contacts of relay 27, 56, 91, contacts of relay 83, 101, 302, contacts of relay 330, 324, 310, 322, wiper 380, number 7 contact upon which it rests to ground. The operation of relays 305 and 310 connect battery to the wire 309 and close the circuit of relay 320 through the cam springs 397 and 398. The operation of relay 320 disconnects the rotary magnet 390 and in its place connects the vertical magnet 395. The operation of this magnet causes the switch G to step vertically.

The operation of relays 830 and 840 (Fig. 35) cause the shifting switch to take another step, disconnecting these relays from the third strip of buttons and connecting them to the fourth strip of buttons. The switch G (Fig. 4) will continue to step vertically until the wipers 365 and 370 engage the tenth set of contacts, whereupon a control circuit is again established as follows: generator 230, number 10 contact, wiper 365, 321, 305, 323, contacts of relay 330, 301, 101, contacts of relay 83, 90, 56, 54, contacts of relay 27, 60, 167, 150, 830, N, 226, number 10 button, condenser 231, number 10 button, 227, 0, contacts of relay 157, 840, 151, 167, 61, 3, contacts of relay 27, 56, 91, contacts of relay 83, 101, 302, contacts of relay 330, 324, 310, 322, wiper 370, number 10 contact to ground.

The operation of relays 305 and 310 again place battery on the wire 309 and close the circuit of the relay 325 through the cam springs 397 and 398. When the switch G was first rotated, it disconnected the relay 315 from the control wire 309, and in its place connected the relay 320 so that it would be operated at the proper time. When the switch G steps vertically, the relay 320 is disconnected and the relay 325 placed in position to be operated by battery placed on the wire 309. The operation of 65 325 disconnects battery from wire 333 and

prevents any further action of either the vertical or rotary magnets.

The operation of relays 830 and 840, when this last contact is found, causes the shifting switch to disconnect them from the fourth strip of buttons and the step which accomplishes this also closes the circuit of the relay 158 as follows: battery B, P, 187, 158 to ground. The operation of this relay closes the circuit of the stepping magnet 161 and also places ground on the control spring 231 so that it can operate the relay 163 and interrupt its own circuit. The interrupting circuit thus established causes the shifting switch to rotate until it reaches its normal position. Just before reaching this position, the wiper of P closes the circuit of the release magnet 166 of the key-set switch M causing it to restore to its normal position thereby disconnecting the operator and the controlling device from the main trunk.

Referring now to Fig. 4, as soon as the relays 305 and 310 become deenergized after their last action, the wipers of the switch G are in engagement with the contacts of the wanted line and the relay 330 is connected in series with the cut-off relay of the called line as follows: battery B, contacts of relay 305, 336, contacts of relay 325, 326, 330, contacts of relay 310, wiper 360 to ground through the cut-off relay of the called line. The relay 330 now becoming energized places battery to the tip relay 335 and ground to the retardation coil 340, thus supplying talking current to the called line. The action of this relay also closes the circuit of the ringing relay 350 as follows: battery B, 329, contacts of relay 325, 331, 350, commutator 500 to ground. The test relay 345 was connected to the wiper 360 when the relays 305 and 310 were energized the last time and if the line had been busy, the relay 345 would have become energized and closed the circuit of the release magnet 335, restoring the switch G to its normal position. This relay 345 will remain energized by ground over the test wire 308 and connect a suitable busy tone to the calling subscriber notifying him that the line was busy.

The ringing relay 350 will act at intervals and place generator to the called line, and when the called subscriber removes his receiver during a silent interval, the tip relay 335 will become energized. The energizing of this relay disconnects the two relays 320 and 315 by disconnecting battery from their locking contacts and also places ground on the test wire 308 rendering the connector switch busy so long as he has control of it. When the relay 320 falls back it removes battery from the locking contact of relay 325. When relay 325 falls back it disconnects battery formerly supplied to relay 330, through the contacts of relay 305. The cir-

cuit of relay 330, however, is maintained by the action of relay 335 which places battery to the winding of relay 330 before the relay 325 falls back. After the parties are 5 through talking, the called subscriber, upon hanging up his receiver, causes the relay 335 to fall back and close the circuit of the release magnet 385 as follows: battery B, contacts of relay 335, 314, contacts of relay 315, 10 385, 322, cam springs 397 to ground. The action of this release magnet restores the switch G to its normal position. The calling subscriber upon hanging up his receiver causes the tip relay 23 (Fig. 2) to fall back, thereby 15 closing the circuit of the release magnet 32 as follows: battery B, cam springs 38, 73, contacts of relay 23, 58, contacts of relay 28, 72, 32, 75, cam springs 41 to ground. The operation of this magnet causes the switch 20 C to return to its normal position opening the cam springs 38, thereby removing battery B from the wire 73 allowing the circuit of the release magnet 35 of the switch D to become energized over the following path: 25 battery B, 35, 73, contacts of relay 23, 58, contacts of relay 28, 72, 32, 75 to ground through the cam springs 41. The operation of relay 35 restores the switch D, thereby opening the cam springs 41 and disconnecting 30 the energizing circuit for the release magnets. As soon as the test wiper 57 of the first selector switch leaves the test contact, then the relay 811 (Fig. 3) falls back and closes the circuit of the release magnet 86 as follows: battery B, contacts of relay 811, 35 86, 89, cam springs 95 to ground. The operation of this magnet causes the switch E to restore and open the release circuit.

In case the called party does not answer, 40 then the calling party has complete control of all the switches and releases the primary, first and second selectors in the manner just described. The releasing of the second selector switch (Fig. 3) removes ground from 45 the test wire 308, disconnects all three relays 315, 320 and 325, thereby closing the circuit of the release magnet 385 just as though the called subscriber had answered and then hung up his receiver.

50 It will be noted that two separate control relays 81 and 82 are shown in Fig. 2, but in practice it would be advisable to combine these two relays in one, having two separate windings. This would also be true 55 in connection with the control relays 84, 85 and 305, 310 and 830, 840.

In Figs. 2, 3 and 4 I have shown various 60 circuits shifted by means of cam springs operated by the switches D, E and G. These cam springs of course are to be adjusted so that only one circuit will be established 65 during any one action of the control relays 81, 82 and 84, 85 and 305, 310. For instance in Fig. 2 relay 29 is operated through the normally closed rotary cam springs 41

by the action of either or both control relays 81 or 82. These relays are deenergized by the wipers 48 and 49 leaving the contacts or by the action of the shifting switch (Fig. 7) before the cam springs can connect the relay 27.

Having thus described my invention, what I desire to secure by Letters Patent is:

1. In a telephone exchange system, a plurality of lines, automatic switches for interconnecting the same and a control device therefor comprising means to selectively associate with said switch, circuits of different electrical dimensions irrespective of the state of activity of the switch, and control magnets for each switch responsive to control from a circuit of an electrical dimension dependent upon the position of the switch.

2. In a telephone exchange system, a plurality of lines to be interconnected, automatic switches for interconnecting them, and control means for said switches comprising a digital set of control circuits at a control station having individually permanently established electrical dimensions, a coacting set of circuits associated with each switch, and switch control magnets arranged to be connected with said circuits for control thereby.

3. In a telephone exchange system, a plurality of lines to be interconnected, automatic switches for interconnecting them, and control means for said switches comprising a digital set of control circuits having different but immobile electrical characteristics, a switch control magnet for each switch responding to control over one or another of said control circuits depending upon the position of the switch, and means to associate any desired one of said control circuits with said switch control magnet.

4. In a telephone exchange system, in combination switching mechanism and contact arms therefor, contacts associated with said switching mechanism engageable by said contact arms; an operator's key-board, actuating means apart from said key-board for the switching mechanism, a control circuit extending between the switching mechanism and key-board; means rendered operable over said control circuit when the contact arms engage contacts corresponding to the indication on the key-board, to disable said actuating means and disconnect said key-board.

5. In a telephone exchange system, in combination a link circuit comprising a series of automatic switches and contact arms therefor, contacts for the automatic switches engageable by the contact arms, an operator's key-board consisting of a series of rows of keys apportioned to the automatic switches, actuating means apart from said

- key-board for said automatic switches, a control circuit extending between the automatic switches and key-board; means rendered operable over said control circuit to 5 disable the actuating means of an automatic switch of the series when its contact arms engage contacts indicated by its apportioned row of keys, together with means in said control circuit for connecting the next row 10 of keys in the series.
6. In a telephone system, the combination with an automatic switch having a bank of contacts and contactors associated therewith, of means for designating the contact 15 to be connected to a contactor, means independent of the designating means for actuating the switch and means for disabling the actuating means when the contactor engages the contact designated.
- 20 7. In a telephone exchange system, the combination of a switching mechanism having a bank of contacts and a contactor associated therewith, a plurality of combinations of circuits associated with certain of 25 the contacts, another plurality of combinations of circuits adapted to be connected one at a time with the contactor, means for actuating the switching mechanism to move said contactor into successive engagement 30 with the contacts, and means for disabling the actuating means when the contactor engages a contact, the circuit of which is energized by the engagement of said contact by the contactor.
- 35 8. In a telephone exchange system, the combination with switching mechanism having contacts and contactors associated therewith, of a plurality of combinations of circuits connected with certain of the contacts, 40 another plurality of combinations of circuits including a circuit passive for connecting the other circuits with the contactors, means for actuating the switching mechanism to move said contactors successively 45 into engagement with the contacts, and means associated with the passive circuit for disabling the actuating means when the contactors engage contacts, the circuit in which said contacts are included being energized by the engagement of said contacts 50 by the contactors.
- 55 9. In a telephone exchange system, the combination with switching mechanism having contacts and contactors associated therewith, a plurality of combinations of circuits connected with certain of the contacts, an operator's key-set, another plurality of combinations of circuits associated with the key-set, means including a key and a circuit for 60 connecting said other combinations of circuits with the contactors on the switching mechanism, means for actuating the switching mechanism to move the contactors into successive engagement with the contacts, and 65 means for disabling the actuating means when the contactors engage certain contacts, the circuit in which said contacts are included thereby forming a part of and completing the connecting circuit.
10. In a telephone exchange system, the combination with automatic switching mechanism having contacts and wipers associated therewith, lines terminating in certain of the contacts, one of the wipers adapted to engage said contacts connected to said 75 lines, a plurality of combinations of circuits connected with certain other contacts, an operator's key set, another plurality of combinations of circuits associated with the key set, means including keys for designating 80 the line and contact wanted, and a circuit for connecting said other combinations of circuits to certain of the wipers, means for actuating the switching mechanism to move the wipers into successive engagement with 85 the contacts, means including a relay in said connecting circuit for disabling the actuating means, the connecting circuit being completed and becoming active when wipers 90 engage a contact or contacts of said other contacts designated by the key, thereby energizing the relay and bringing the wiper adapted to engage contacts connected to said lines to rest on the contact associated with the line wanted. 95
11. In a telephone exchange system, the combination with automatic switching mechanism having contacts associated therewith, of actuating means for the switching mechanism, a wiper adapted to engage certain of 100 the contacts, other wipers adapted to cooperate with certain other contacts and at times to establish circuit combinations to disable the actuating means and bring the first-mentioned wiper to rest in engagement 105 with a predetermined contact.
12. In a telephone exchange system, the combination with automatic switching mechanism including selector and connector switches having banks of contacts and contactors associated therewith, of link circuits 110 interconnecting the switches, subscribers' lines terminating in the connector switches, actuating means for the switches, a plurality of combinations of circuits connected with certain of the contacts, an operator's key set comprising a plurality of rows of keys, another plurality of combinations of circuits associated with the operator's key set and controlled by said keys, means for 115 connecting the circuit combinations designated by a key or keys depressed in succession to the selector and connector switch contactors, and means for disabling the actuating means of each switch when the contactors thereof engage contacts in the switch designated by a key or keys depressed. 120
13. Controlling system for automatic switches comprising testing means associated with each switch and adapted to connect 125 130

- successively with differently characterized test circuits and means for rendering said testing means responsive to a predetermined one of said test circuits to disable the actuating means of this associated switch. 5
14. Automatic switching systems for telephone exchanges comprising automatic switching mechanism adapted to connect successively with different connective circuits, differently characterized test circuits associated with said connective circuits, differently characterized control circuits each corresponding to a different test circuit, and testing means associated with said testing circuits operative only when corresponding characterized circuits are connected in series. 10
15. The method of selectively connecting a given connecting telephone circuit with any desired one of a group of extension circuits to extend a connection, which method consists in maintaining in connection with each of said group of circuits, a differently characterized testing condition, at will establishing a testing condition on said given circuit adapted to coact with the testing condition appertaining to the particular circuit with which connection of the group is desired, successively bringing the terminals of said given circuit into juxtaposition with the terminals of the circuits of said group until coaction of said conditions results, and determining the desired connection through the coaction of said conditions. 15
16. The method of selectively connecting a given connecting telephone circuit with any desired one of a group of extension circuits to extend a connection, which method consists in maintaining in connection with each of said group of circuits, a differently characterized testing condition, at will establishing a testing condition on said given circuit adapted to coact with the testing condition appertaining to the particular circuit with which connection of the group is desired, successively bringing the terminals of said given circuit into juxtaposition with the terminals of the circuits of said group until coaction of said conditions results, and determining the desired connection through the coaction of said conditions. 20
